UNITED STATES PATENT OFFICE.

LOUIS ROMANELLI, OF CHICAGO, ILLINOIS.

DESIGN FOR A RADIO LOUD SPEAKER.

Application filed February 27, 1925. Serial No. 12,504. Term of patent 3½ years.

To all whom it may concern:

Be it known that I, LOUIS ROMANELLI, a subject of the King of Italy, who has declared his intention of becoming a citizen of the United States, and residing in the city of Chicago, county of Cook, and State of Illinois, have invented a new, original, and ornamental Design for Radio Loud Speaker, of which the following is the specification, reference being had to the accompanying drawing, forming a part thereof.

On the drawings:

Figure 1 is a front elevation of a radio loud speaker illustrating the design embodying my invention.

Figure 2 is a side elevation thereof.

I claim:

The ornamental design for a radio loud speaker as shown.

LOUIS ROMANELLI.
